CLAIM

The ornamental design for a suspender strap buckle with tool dock, as shown and described.

DESCRIPTION

FIG. 1 is a perspective view of a suspender strap buckle with tool dock showing the new design with a fly fishing tool attached to the tool dock.

FIG. 2 is a front view of a suspender strap buckle with tool dock showing the new design.

FIG. 3 is a rear view of a suspender strap buckle with tool dock showing the new design.

FIG. 4 is a first side view of a suspender strap buckle with tool dock showing the new design.

FIG. 5 is a second side view of a suspender strap buckle with tool dock showing the new design.

FIG. 6 is a top view of a suspender strap buckle with tool dock showing the new design; and,

FIG. 7 is a bottom view of a suspender strap buckle with tool dock showing the new design.

The broken lines shown in the drawings illustrate environmental subject matter that forms no part of the claimed design.
